US0D1031427S

(12) **United States Design Patent** (10) **Patent No.:** **US D1,031,427 S**
(45) **Date of Patent:** **** Jun. 18, 2024**

(54) **GATE STOPPER**

(71) Applicant: **Ningbo Eudemon Child Protective Equipment Co., Ltd.**, Ningbo Zhejiang (CN)

(72) Inventor: **Xu Wang**, Zhejiang (CN)

(73) Assignee: **Ningbo Eudemon Child Protective Equipment Co., Ltd.**, Ningbo Zhejiang (CN)

(**) Term: **15 Years**

(21) Appl. No.: **29/911,296**

(22) Filed: **Aug. 31, 2023**

Related U.S. Application Data

(62) Division of application No. 35/515,592, filed on Nov. 3, 2022 (U.S. filing date under 35 U.S.C. 384), and having an international filing date of Nov. 3, 2022.

(57) **CLAIM**

The ornamental design for a gate stopper, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, left side perspective view of a gate stopper, showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.
